ATTORNEY.

UNITED STATES PATENT OFFICE.

JOHN H. GIBSON, OF CANTON, OHIO.

WRENCH.

SPECIFICATION forming part of Letters Patent No. 431,655, dated July 8, 1890.

Application filed April 7, 1890. Serial No. 346,885. (No model.)

To all whom it may concern:

Be it known that I, JOHN H. GIBSON, a citizen of the United States, and a resident of Canton, county of Stark, State of Ohio, have 5 invented a new and useful Improvement in Wrenches, of which the following is a full, clear, and exact description, reference being had to the accompanying drawings, making part of this specification.

10 My invention relates to improvements in wrenches, and particularly to that class known as "quick-moving monkey-wrenches;" and it consists of certain features of construction and combination of parts, as will be herein- 15 after described, and pointed out in the claim.

Figure 1 is a view in perspective of a wrench illustrating my invention; Fig. 2, a side elevation, partly sectional; Fig. 3, a perspective of a tightening-wedge; Fig. 4, a similar view 20 of the tightening-band, screw, or nut; and Fig. 5, a similar view of the sliding or movable jaw.

Similar letters of reference indicate corresponding parts in all of the figures of the 25 drawings.

The wrench-bar A, the stationary jaw B, and the handle C are of a well-known and approved form, and may be made of any suitable material. The sliding jaw D may be 30 made of any suitable cast metal, preferably cast malleable iron or steel. On the back edge of the wrench-bar A is provided a series of notches a. The sliding jaw D is formed substantially as shown in the drawings, having 35 an aperture c, through which the bar A is passed, the heel portion having a recess d, in which is placed a rack e, adapted to the recess d, and having a series of teeth f, corresponding with and adapted to engage the 40 notches a on the back of the bar A. On the opposite side of the bar, in the toe end of the jaw, is provided an inclined plane g, and on the handle side of said jaw oval cheeks h are provided, projecting from said jaw on each 45 side of the bar toward the handle. Said cheeks h are provided with annular screw- threads j.

To secure the teeth f of the rack e in engagement with the notches a of the bar and 50 the jaw against movement on the said bar, a wedge E is provided, having one of its sides k a flat or plane surface to rest and slide upon the bar A, the other or opposite side an

inclined plane m to correspond with the plane g in the jaw, and a neck portion n, circular 55 in cross-section. On the ends of said neck portion is provided shoulders o, adapted to engage the tightening-nut F, said nut having an annular thread p, corresponding with the thread f on the cheek portions of the jaw D. 60

In construction the jaw D, with the rack e placed therein, is placed on the bar, the nut with the neck of the wedge placed therein, as shown in Fig. 2, passed on the bar, the wedge entering the jaw, the nut turned onto 65 the cheeks will carry the wedge in against the plane g.

In operation, to tighten the jaw to the bar at any desired adjustment the nut is turned on the side or cheek portion of the jaw, driving 70 the wedge against the plane in the jaw to draw the rack-teeth f into the notches a on the bar, by which engagement the jaw is secured to the bar, and to release the jaw it is only necessary to reverse the nut one-half of 75 a revolution to release the teeth f from the notches a in the handle-bar, after which the jaw may be moved on said bar to a desired point and again secured by turning the nut to wedge the teeth f again in engagement with 80 the notches a.

It will be noticed that by the construction hereinbefore described a quick-moving wrench may be constructed embracing the simplicity and durability of the slow-moving 85 but well-known screw or monkey wrench.

Having thus fully described the nature and object of my invention, what I claim as new, and desire to secure by Letters Patent, is—

The combination, in a wrench, of the handle-bar A, having thereon a series of notches a and a fixed jaw B, a movable jaw D, having therein a rack e to engage said notches, a plane m, and a wedge E to engage said plane, threaded side cheeks b and a tightening-nut 95 F about said handle-bar to engage the thread on said cheeks, and the wedge E to draw the teeth f into the notches a on the handle-bar, as described, and for the purpose set forth.

In testimony whereof I have hereunto set 100 my hand this 31st day of March, A. D. 1890.

JOHN H. GIBSON.
